UNITED STATES PATENT OFFICE.

FREDERICK A. BALLOU, OF NAYATT, AND ROGERS T. STAFFORD, OF EAST PROVIDENCE, RHODE ISLAND, ASSIGNEES TO B. A. BALLOU & CO., INC., OF PROVIDENCE, RHODE ISLAND, A CORPORATION OF RHODE ISLAND.

SHOE STRAP.

Application filed March 10, 1927. Serial No. 174,317.

This invention relates to an improved construction of cross strap for shoes; and has for its object to provide a shoe strap of this character having an attaching member on 5 one or both of its opposite ends to be detachably connected to the margins of the shoe upper, the strap being arranged to extend over the instep of the wearer for ornamental purposes, or to assist in retaining the 10 shoe in position on the foot, or both.

A further object of the invention is to form the strap flexible and extendible with clamping or gripping members on its opposite ends by which the device may be detachably connected to the opposite margins of 15 the shoe upper.

A still further object of the invention is to form the strap of a plurality of metal extendible links and in some cases to mount 20 an ornament on the same, to be attached to the shoe and extend over the instep of the wearer.

With these and other objects in view, the invention consists of certain novel features 25 of construction, as will be more fully described, and particularly pointed out in the appended claims.

In the accompanying drawings:

Figure 1 is a perspective view illustrating 30 our improved instep strap as applied to a shoe.

Figure 2 is a top view showing the strap ornament with metal extendible links attached to either side thereof.

Figure 3 is an edge view of the metal ornament showing the attaching members on its ends to which the links of the strap are connected.

Figure 4 is a view showing the under side 40 of a plurality of metal links of the instep strap and showing the same having an attaching member at one end and the opposite end of this link section being attached to an ornament.

Figure 5 is an edge view of the link sections shown in Figure 4, in extended position and partly in section.

Figure 6 is a section on line 6-6 of Figure 1 and shows the metal strap as formed 50 in two sections and attached to the opposite margins of the shoe upper, one end portion of each of the strap sections being connected to an ornament.

Figure 7 is the same as Figure 6 and showing the metal links as formed into a continuous chain, all of the same size with a separate ornament supported thereon.

It is often desirable by wearers of that style of shoe known as a pump or slipper, of advantage to provide a cross strap to extend 60 over the ankle or instep as an ornament, or for the purpose of assisting in retaining the shoe on the foot, and it is also often found of particular advantage to form this strap 65 flexible. It is also found that this strap may be made extremely ornamental and attractive if made of metal and in order to form a metal strap which is comfortable on the foot it should be made both flexible and extendible; and it is also found of advantage 70 to so form this metal strap that it may be readily attached to different shoes and detached therefrom to be applied to other shoes, without the necessity of providing a permanent attachment on the shoe which in 75 some cases disfigures the same, and one way of accomplishing this result is by providing clamping members on the strap ends by which the strap may be readily connected to and disconnected from the opposite side 80 margins of the shoe to exert a flexible tension on the instep of the wearer to assist in retaining the shoe in position on the foot; and the following is a detailed description of the present embodiment of our invention 85 and showing one construction of strap by which these advantageous results may be accomplished:

With reference to the drawings, 10 designates a metal strap which is formed of a 90 plurality of link units, each comprising essentially an outer box link 11 and an inner slide link 12, one end of the slide link within the box link being pressed towards contracted position by a spring 13, whereby 95 each link unit is adapted to receive a sliding endways extension and contracting action to exert a flexible tension over the instep of the wearer to assist in retaining the shoe on the foot.

At each end of this flexible chain section, we have flexibly connected a clamping, gripping or attaching member 14, which is an extension or part of the strap, the gripping portion of the strap herein illustrated comprising a body portion 15 with a front jaw 100

- portion 20 and in this body is hingedly mounted a cooperating biting tongue or jaw member 16 one end 19 of this tongue extending through a spring plate 17 in the body 5 which is arranged to retain the tongue when in open position and also to exert a strong closing and gripping action towards this body jaw to cooperate therewith in clamping onto the side margins 21 of the shoe.
- 10 The tongue is provided with a spur 18 so that when swung forward into gripping position it will bite into the inner surface of the shoe and securely attach the strap end thereto. The extendible metal chain 15 may be constructed with links all of the same size if desired and when provided with the clamping members 14 at each end it may be detachably connected to the opposite sides of the shoe upper, as shown in Figure 7, and 20 on these links, in some instances, may be mounted an ornament 22, if desired, while in other instances, as illustrated in Figures 1 and 6, one of the links of the chain may be enlarged if desired and made in the form 25 of an ornament 23, the opposite ends of the ornament being provided with hook-shaped attaching members 24 to which an end link 25 of the strap may be flexibly connected, if desired.
- 30 We have herein shown an instep strap for a shoe as formed of extendible metal links with attaching members at the ends thereof but we do not wish to be restricted to this exact construction of strap as any ornamental 35 strap having attaching members at its ends to be connected to opposite side margins of the shoe, or any ornamental extendible metal strap which may be detachably connected at either one or both of its ends to the shoe, 40 will fall within the spirit and scope of this invention.

Mention is made of our Patent No. 1,640,104, dated August 23, 1927, which broadly claims this invention in its ornamental aspect.

45 The foregoing description is directed solely towards the construction illustrated but we desire it to be understood that we reserve the privilege of resorting to all the mechanical changes to which the device is susceptible, the invention being defined and limited only by the terms of the appended claims.

We claim:

- 50 1. A shoe strap unit of a length to extend over the instep of the wearer and substantially to the opposite margins of the shoe, a pair of jaws carried by said strap, and spur means associated with one of the jaws 55 to engage the margins of the shoe to assist 60 in holding the strap in position on the shoe

while permitting said strap to swing relatively to the margins of the shoe.

2. A shoe strap of a length to extend over the instep of the wearer to engage the opposite margins of the shoe upper, a tongue on each end of said strap hingedly connected thereto to engage the opposite surfaces of the margins of the shoe, and a spur on one of the margin-engaging parts to engage the shoe to assist in holding the strap in position while permitting the strap to swing relatively to the margin of the shoe.

3. A shoe strap of a length to extend over the instep of the wearer with the ends engaging the outer surface of the opposite side 75 margins of the shoe, a tongue hingedly connected to each end of the strap to engage the inner surface of the shoe margin, and a single spur on each tongue to engage the margin of the shoe to assist in holding the 80 strap in position while permitting the strap to swing relative to the margin of the shoe, the tongue on each end being movable on its hinge to detach the strap ends from the margins of the shoe.

4. A shoe strap comprising a series of units, hingedly connected together of a length to extend over the instep of the wearer and over the opposite side margins of the shoe for engagement therewith, a tongue carried by each end unit to engage the inner surface of the shoe margin forming with each end unit a clamp for ready complete attachment or detachment of the strap, and a single spur on said tongue to engage the 95 inner portion of the shoe margin to assist in holding the strap in position while permitting the strap to swing relative to the margin of the shoe.

5. A shoe strap comprising a series of 100 units, hingedly connected together of a length to extend over the instep of the wearer and over the opposite side margins of the shoe upper for engagement therewith, some of said units including parts 105 slideable telescopically on each other with a spring acting between said parts to move them to contracted position, a tongue carried by each end unit to engage the inner surface of the shoe margin forming with each end unit a 110 clamp for ready complete attachment or detachment of the strap, and a single spur on said tongue to engage the inner portion of the shoe margin to assist in holding the strap in position while permitting the strap to swing relative to the margin of the shoe.

115 In testimony whereof we affix our signatures.

FREDERICK A. BALLOU.
